CURTAIN ROD

Hermann Karl Cymara, Ithaca, N.Y.

Application June 7, 1957, Serial No. 664,295

3 Claims. (Cl. 211—105.3)

This invention relates to hangers for supporting curtain rods such as used with window curtains and other draperies, and its general purpose is to provide a more convenient way for installing such rods. One of the objects is to make a curtain rod assembly that can be used on the top edge of a window frame and not require the services of a skilled person to fasten it in place or adjust it to a desirable position. Also if desired the device can be modified without tools to attach to flat vertical areas instead of the horizontal top edge of a window frame. A principal purpose in its preferred form is to avoid leaving any permanent marks on the front face of a window frame so that a later tenant who may choose to hang curtains differently will not find the window casing defaced. The device is intended for sale to the unskilled public and can be put up neatly without any tools beyond an ordinary hammer.

Most curtain rods are supported by brackets fastened on the front face of the part of a window frame that extends above a window. As such brackets take up considerable space, the rod is usually located an inch or two below the top of the casing. While some people like their curtains hung that way and have no objection to the window casing showing above the curtain, others prefer to have the top of the curtains extend up above the top of the window casing so as to completely conceal it. For that purpose various forms of curtain rod hangers have been proposed, but their installation often has involved a type of forethought and precision more characteristic of a carpenter than an average tenant or householder.

The curtain hanger under the present invention can be installed by anyone capable of driving a few nails in an approximate position, and yet will present a neat and straight appearance regardless of errors in driving the nails. Furthermore, if the purchaser should change his mind while installing the rods and wish that he had hung the curtains lower and on the front face of the casing instead of concealing the top, he does not have to return the rod to a store or buy a new one, but can without tools change the conformation so as to provide a front face installation. These features make the rod easier to manufacture and sell, and extend its utility for more universal use.

Referring now to the drawings forming part of this specification,

Fig. 1 is a perspective view of the curtain rod as generally installed on the upper edge of a window frame casing.

Fig. 2 is a detail view showing how it can be modified for installation on the front face of a window casing or other vertical surface.

Fig. 3 is an exploded view showing the various parts of the leveling adjustment provided on the ends of the arms.

Similar reference numerals refer to similar parts throughout the various views.

As shown in Fig. 1, the curtain rod 1 usually made

2

in telescoping sections so as to adjust easily to windows of various widths, has at right angles at its ends a pair of arms 2 to hold the rod 1 out from the window casing 3. The rod 1 and arms 2 are preferably made of sheet brass or other metal so as to be light in weight, easy to manufacture, and pleasing in appearance.

Each arm 2 terminates in an upper flat overhanging lip or projection 4 capable of extending over on to the top upper face or edge 3' of the window casing 3. The extension 4 has a hole 5 adapted to slip over the head of a small nail 6 which may be driven into the top of the casing 3. If the nails 6 are not driven in quite the right location, other nails 6' may also be driven without disfiguring the window frame, since they are above the eye level where they are not visible from the floor. The end of each arm 2 below the lip 4 has a vertical face 7 adapted to extend approximately parallel to the front face 3" of the wall or window casing 3.

In order to install the curtain rod over a window, it is generally only necessary to drive a pair of small nails 6 as shown; but unless they have been driven in precisely the correct location the curtain rod 1 will probably hang down unevenly and not hold the curtain up properly. To remedy that defect and correct for errors in carpentry, an adjusting screw 10 is provided in the lower end portion of each arm 2, whereby each end of the arm can be raised or lowered. The adjusting screw or bolt 10 lies in a fold or groove 11 at the lower part of the arm 2. The arm is usually made of sheet metal in which such a groove is easily shaped. Each such screw 10 is provided with a head 12 which can bear against the front face 3" of the window casing 3 without marring it. A nut 14 on each screw 10 fits in a slot or notch 15 located in the lower part of the arm 2 so that as the screw 10 is turned the curtain rod 3 will be raised or lowered to the desired level. Thus the curtain rod can be accurately installed to suit the conditions to the satisfaction of the purchaser regardless of any errors made in driving the nails 6.

The curtain rod mounting above described is primarily intended for mounting on the top of a window casing so that no blemish will appear on the more visible front face of the casing. However, if the purchaser should become dissatisfied with that type of mounting, he can readily convert it to a front face mounting by bending the flat lip 4 up at right angles as shown at 4' in Fig. 2 and Fig. 3. This can then either be fastened to the front face 3" of the window casing 3 by the screw 17 as shown in Fig. 2, or a small nail similar to 6 or 6' may be driven diagonally at a steep slant down in the front face 3" of the casing and the hole 5 of the lip 4' be then slipped down over it in place of the screw. In either event the rod level can be adjusted by turning the screw 10 with the fingers just as in the other mounting first described. When a pair of such small nails as 6 are used, the holes 5 in the extension lips 4 are enough larger than the nail heads so that the curtains and rods can be easily lifted off for cleaning without removing the nails.

While I have in the foregoing described certain specific forms by way of example, it will be understood that they are merely for the purpose of illustration to make clear the principles of the invention, which is not limited to the particular forms shown but is susceptible to various modifications and adaptations in different installations as will be apparent to those skilled in the art without departing from the scope of the invention as stated in the following claims.

I claim:

1. In a curtain rod hanger, the combination of an adjustable curtain rod having an arm at each end adapted to extend toward a casing for attachment thereto, each

such arm terminating at its upper part in an overhanging projection adapted to extend horizontally over a top upper edge of the casing, the overhanging projections having holes adapted to slip over nails that may be driven downward into said top upper edge of the casing, an adjusting screw on each arm located below the overhanging projection of said arm and adjustable against a vertical face of the casing so as to raise or lower the arms using the holes in the overhanging projections as pivots and thereby level the curtain rod without marring said vertical face of the casing, whereby curtains may be readily installed and removed at high level.

2. In a curtain rod hanger, the combination of an adjustable curtain rod having an arm at each end adapted to extend toward a casing for attachment thereto, each such arm terminating at its upper part in an overhanging projection adapted to extend horizontally over a top upper edge of the casing, the overhanging projections having holes adapted to slip over nails that may be driven downward into said top upper edge of the casing, an adjusting screw on each arm located in a channel below and substantially parallel to the overhanging projection of said arm and adjustable against a vertical face of the casing so as to raise or lower the arms using the holes in the overhanging projections as pivots and there-

by level the curtain rod without marring said vertical face of the casing, whereby curtains may be readily installed and removed at a high level.

3. In a curtain rod hanger, the combination of an adjustable curtain rod having an arm at each end adapted to extend toward a casing for attachment thereto, each such arm terminating at its upper part in an overhanging projection adapted to extend horizontally over a top upper edge of the casing, the overhanging projections having holes adapted to slip over nails that may be driven downward into said top upper edge of the casing, a nut in the lower part of each of said arms, an adjusting screw on each arm located below the overhanging projection of said arm and adjustable in the nut with its head against a vertical face of the casing so as to raise or lower the arms using the holes in the overhanging projections as pivots and thereby level the curtain rod without marring said vertical face of the casing, whereby curtains may be readily installed and removed at a high level.
